Primary Examiner — Garth Rademaker*Assistant Examiner* — Richard Kearney(74) Attorney, Agent, or Firm — Sughrue Mion, PLLC(57) CLAIM

The ornamental design for a toner cartridge, as shown and described.

DESCRIPTION

FIG. 1 is a front, left, top perspective view of a toner cartridge showing our new design;

FIG. 2 is a rear, right, bottom perspective view thereof;

FIG. 3 is a front view thereof;

FIG. 4 is a rear side view thereof;

FIG. 5 is a left side view thereof;

FIG. 6 is a right side view thereof;

FIG. 7 is a top plan view thereof; and,

FIG. 8 is a bottom plan view thereof.

The broken lines in the Figures show portions of the toner cartridge which form no part of the claim.
